UNITED STATES PATENT OFFICE.

ORRIN WEIDRICH, OF HAMILTON, ONTARIO, CANADA.

SLIDING-DOOR HANGER AND TRACK.

1,054,377.

Specification of Letters Patent.

Patented Feb. 25, 1913.

Original application filed October 7, 1912, Serial No. 724,349. Divided and this application filed November 18, 1912. Serial No. 732,058.

To all whom it may concern:

Be it known that I, ORRIN WEIDRICH, a subject of the King of Great Britain, and a citizen of the Dominion of Canada, residing 5 at 202 Wentworth street north, in the city of Hamilton, in the county of Wentworth and Province of Ontario, Dominion of Canada, have invented certain new and useful 10 Improvements in Sliding-Door Hangers and Tracks, of which the following is a specification.

This invention relates to sliding-door 15 hangers and tracks, and more particularly to that type of device used in connection with the suspended doors of barns, grain 20 warehouses, railroad freight cars and the like.

This invention is a divisional from my 25 pending application, Serial No. 724,349, filed October 7th, 1912.

The main object of my invention is to provide an improved combined door hanger and track adapted to be constructed from a single piece of sheet metal at a very small 25 cost, and one which will provide the necessary trackway for the wheels of the hanger in one piece with the housing structure.

With these and other objects in view as 30 will be apparent from the following description, my invention consists in the novel construction, arrangement and combinations of parts hereinafter fully described, and particularly pointed out by the appended claims.

35 The accompanying drawing, forming a part of this specification, is an illustration of the invention, and exemplifies by a sectional elevation the adaptation of my improvements to a sliding door hanger and 40 track suitable for grain warehouses and the like.

According to my invention, I construct 45 the track from thin sheet metal, preferably galvanized iron, and form it with a vertical flange 1, for fixture against the wall or other structure to which the device is applied as by bolts 2, 2, for example. Obliquely inclined relative to said flange 1, I outwardly bend the sheet of metal to constitute a roofing 50 3, and then downwardly bend said sheet to form a substantially vertical front facing 4. The material is bent inwardly at the 55 lower edge of the front facing 4 to form a basal flange 5, which terminates in a longitudinally extending tubular portion 7, said

tubular portion constituting a trackway or running surface 6. This structure not only provides great strength, but while providing all necessary rigidity, it is sufficiently elastic to prevent the device from being unduly noisy in operation.

The hangers proper are constructed as follows:—8, is one of the wheels suitably grooved about its peripheral surface to snugly fit the aforesaid running surface 6, 65 and said wheels may be either made entirely of compressed fiber, cast metal, or fiber sheathed with a steel rim or tire. The wheel 8, is loosely mounted upon a stub-axle 9, provided with a head 10, adapted to fit 70 snugly against the said wheel 8, on its front face; and, to insure easy running, I use anti-friction rollers 11, around said stub-axle 9.

12, is a spring washer, and 13, is a threaded extension of the stub axle 9, which 75 is screwed into the hanger head 14, and afterward riveted over at 15, as will be clearly understood on an examination of the drawing; a cross-cut—not shown—being provided in the head 10, for the screwing 80 operation, while the riveting over at 15, insures absolute rigidity.

16, is the upper portion of the hanger, and it is preferably formed as shown; that is to say, the lower part thereof is fashioned 85 with hinge ears 17, to which the lower hanger portion 18, is hingedly connected by a through bolt or pin 19.

20, is a laterally projecting trough formed integral with the lower part of the upper 90 hanger portion 16, and it has spaced relation to the tubular track 7, aforesaid.

Obviously, two or more hangers will be employed in connection with each door 21, which is suspended by bolts 22, from the 95 lower hanger portion 18, and I wish it clearly understood that I have only illustrated one hanger as the general arrangement of the entire device will be well known to those skilled in the art to which my invention appertains.

When the track is supported in position with the wheels 8, in place, I close in the ends of the said track by cap pieces—not shown—to prevent small birds and vermin 105 from entering and fouling same.

From the foregoing description and accompanying drawings it will be readily seen that the suspended door 21, may be swung forwardly or upwardly, as well as longitu- 110

dinarily moved without fear of damaging or disconnecting the several parts. Furthermore by making the track 7, of the cross-section shown, the wheels 8, will be kept 5 properly positioned, while the tubular formation of the track 7, effectively prevents the ingress of dirt or rain and the like which interfere with the easy working of the device as well as tend to deteriorate the metal.

10 Obviously changes in the shape, proportions, and minor details may be effected without in any way departing from the spirit and scope of the invention, and it is intended to include all such within this application and as limited by the appended claims.

Having thus fully described my invention, what I claim as new and desire to secure by Letters Patent, is:—

20 1. The combination in a device of the type described of a track formed with a suspension flange, a roofing integral therewith and projecting obliquely from the lower edge thereof and downwardly bent to constitute a front facing lying in a plane substantially vertical and parallel to said suspension flange, said front facing being in-

wardly turned at its lower parts into a horizontal plane and longitudinally grooved to constitute a tubular running way, wheels 30 adapted to fit and traverse said tubular running way loosely mounted on stub-axles secured to the heads of upper hanger portions, said upper hanger portions being furnished with laterally projecting upwardly 35 curved flanges adapted to prevent the track from being outwardly strained, and means for suspending said track in position and fixing said hangers to the door, substantially as set forth.

2. A track and housing comprising in combination, the suspension flange, an inclined roof extended therefrom, a front facing extending from said roof and a tubular running-way supported from said front facing substantially as shown and specified.

Signed at Hamilton, county of Wentworth, Province of Ontario, Dominion of Canada, this 12th day of November, A. D. 1912.

ORRIN WEIDRICH.

In the presence of—

ALFRED G. BRATTON,
GERTIE NICHOLSON.
